J. B. FREYSINGER.
PIN TUMBLER LOCK.
APPLICATION FILED JAN. 19, 1922.

1,433,362.

Patented Oct. 24, 1922.

Inventor
J. B. Freysinger
By Seymour & Bright
Attorney

UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

PIN-TUMBLER LOCK.

Application filed January 19, 1922. Serial No. 530,337.

To all whom it may concern:

Be it known that I, JOHN B. FREYSINGER, a citizen of the United States, and a resident of Stamford, in the county of Fairfield and State of Connecticut, have invented certain new and useful Improvements in Pin-Tumbler Locks; and I do hereby declare the following to be a full, clear, and exact description of the invention, such as will enable others skilled in the art to which it appertains to make and use the same.

My invention relates to an improvement in pin tumbler locks, the object being to construct the cylinder and housing for the pin tumblers of sheet metal, so as to avoid machine work and thus materially reduce the cost of manufacture without impairing the efficiency or durability of the lock.

With this object in view my invention consists in the details of construction as will be more fully explained and pointed out in the claims.

In the accompanying drawings, Figure 1 is a view in section of the cylinder and tumbler housing the tumblers being shown in elevation; Figure 2 is a view in perspective of the tumbler housing removed from the cylinder; Figure 3 is a similar view of a modified form of cylinder and tumbler housing and Figure 4 is another modification of the housing.

5 represents the cylinder made of sheet metal bent into shape, and provided with openings for pin tumblers 6. These pin tumblers are adapted to enter recesses in a key plug, not shown, mounted to rotate in the cylinder and be lifted by the proper key to release the plug to permit the latter to be turned to actuate the bolt mechanism of a lock or other device, in the usual and well known manner. The edges of the sheet metal blank from which the cylinder 5 is made are preferably brazed or otherwise secured together, and it is preferably provided with shouldered ends 7 to receive the ring shaped ends 8 of the housing 9, and with slots 10 to receive the tongues 12 on said housings so that when the housing is assembled on the cylinder, the parts will be secured against the possibility of independent movement.

The housing is made of sheet metal and comprises a top 11, ends 12 and sides 13, the

ring shaped ends 8 being integral with the ends 12, all of said parts being struck up or stamped from a single sheet of suitable metal, the ends 12 and sides 13 being bent as shown in Figures 1 and 2 to form the housing and guide for the shanks 6^a of the pin tumblers 6. The tumblers 6 pass through openings in the cylinder 5 and enter corresponding holes in the plug, not shown, for locking the latter against rotation, the plug being provided with the usual key slot for the passage of the key which operates in the well known manner to lift the pin tumblers to a position to release the plug so that the latter may be turned by the key.

The shanks 6^a of the pin tumblers pass through holes 14 in the top of the housing 70 and are embraced by springs 15 which bear at their upper ends against the inner face of the top of the housing and at their lower ends against the tumblers 6, or tumbler drivers as the case may be, and tend to hold 75 the tumblers in engagement with the key plug.

The front end 12 of the housing 9 is provided with integral ears 16 each having a rivet hole therethrough for attaching the housing and cylinder 5 carried by the housing to the face plate of the lock.

If desired I may dispense with the ring shaped ends 8, shown in Figures 1 and 2, and attach the housing to the cylinder by the 85 tongues 12^a, dovetailed or otherwise secured to the cylinder as shown in Figure 3, or I may dispense with the front plate 12 of the housing and provide the side member 13 thereof with the forwardly projecting integral tongues 17 adapted to be passed through slots in the face plate of the lock and be riveted thereto.

In all the forms the tumbler housing is made independent of the cylinder, and both 95 parts are made of thin rolled or drawn metal stamped and bent into shape, and as the parts can be stamped with sharp clean lines, accurate fit of the parts can be accomplished without any machine work and consequently 100 at minimum cost.

It is evident that many slight changes might be resorted to in the relative arrangement of parts shown and described without departing from the spirit and scope of my 105 invention hence I would have it understood

that I do not wish to confine myself to the exact construction and arrangement of parts shown and described but,

Having fully described my invention 5 what I claim as new and desire to secure by Letters Patent is:—

1. In a pin tumbler lock, a cylinder formed from a metal blank bent into cylindrical form, a tumbler housing, movable tumblers 10 mounted in openings in the top of the cylinder and also in the top of the housing and free or unsupported between said cylinder and the top of the housing, and springs for normally forcing the tumblers toward and 15 into the cylinder.
2. In a pin tumbler lock, a cylinder and a tumbler housing separate from the cylinder, the said housing having a projection, the said cylinder and housing being made of 20 sheet metal bent into shape and secured together by the projection on the end of the housing engaging the corresponding end of the cylinder.
3. In a pin tumbler lock, a cylinder and 25 a single housing for the entire set of tumblers each made of sheet metal and secured together at their ends, the housing having a closed top, sides and rear end.
4. In a pin tumbler lock, a cylinder and 30 housing each made of sheet metal and connected at their ends, and pin tumblers mounted and guided in the top of the cylinder and the top of the housing and free and unsupported between said cylinder and 35 housing.
5. In a pin tumbler lock, a cylinder and housing each made of sheet metal and bent

into shape, the housing being provided at its ends with ring shaped ends to receive the ends of the cylinder.

6. In a pin tumbler lock, a cylinder and housing each made of sheet metal bent into shape, the housing being provided with ring shaped ends to receive the ends of the cylinder and with projections to enter slots 45 in said ends.

7. In a pin tumbler lock, a cylinder, a sheet metal housing closed at its top, sides and ends and secured to the top of the cylinder, and tumblers guided by and movable 50 in holes in the top of the cylinder and also in the top of the housing.

8. In a pin tumbler lock, a cylinder and a housing secured to the latter, the housing being made of sheet metal, and having folded 55 sides and ends, the front end having side ears with holes through the same for the attachment of a face plate of the lock.

9. In a pin tumbler lock, a sheet metal cylinder formed from a flat blank bent into 60 cylindrical form, a housing made of sheet metal and secured to the top of the cylinder, tumblers mounted in and guided by the top of the cylinder and top of the housing and springs within the housing and bearing 65 against the tumblers for yieldingly holding the latter in their operative position.

In testimony whereof, I have signed this specification in the presence of two subscribing witnesses.

JOHN B. FREYSINGER.
